[57] CLAIM

The ornamental design for a pneumatic sporting gun for
underwater hunting, as shown.

DESCRIPTION

FIG. 1 is a side elevational view of a first embodiment of
said pneumatic sporting gun for underwater hunting;

FIG. 2 is a top plan view thereof;

FIG. 3 is a front elevational view thereof;

FIG. 4 is a side elevational view thereof of a side opposite
to that shown in FIG. 1;

FIG. 5 is a bottom plan view thereof; and,

FIG. 6 is a rear elevational view thereof.
